UNITED STATES PATENT OFFICE.

CARL E. BROWN, OF COLUMBUS, OHIO.

OIL-BURNER.

1,344,978.

Specification of Letters Patent. Patented June 29, 1920.

Application filed August 20, 1919. Serial No. 318,713.

To all whom it may concern:

Be it known that I, CARL E. BROWN, a citizen of the United States, residing at Columbus, in the county of Franklin and 5 State of Ohio, have invented a new and useful Oil-Burner, of which the following is a specification.

The device forming the subject matter of this application is an oil burner, and the 10 invention aims to provide novel means whereby a quantity of oil, constituting a priming charge, may be deposited in a priming tray, or on a mass of absorbent material.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, within 25 in the scope of what is claimed, changes in the precise embodiment of the invention shown can be made without departing from the spirit of the invention.

In the drawings:—

30 Figure 1 shows in top plan, a device constructed in accordance with the invention; Fig. 2 is a longitudinal section wherein parts remain in elevation; Fig. 3 is a cross section on the line 3—3 of Fig. 2; and Fig. 35 4 is a cross section on the line 4—4 of Fig. 2.

In carrying out the invention, there is provided a box-like casing, denoted generally by the numeral 1, the casing including a body 2, open at the lower end, and closed 40 at its upper end by a removable top 3, held in place by a flange 4 on the top 3, the flange coacting with the body. Intermediate its ends, the top 3 is provided with a priming tray 5 adapted to receive absorbent material 6, which may be asbestos or ashes. The top 3 is supplied with openings 7 communicating with the interior of the body 2, the openings 7 being located at the ends of the priming tray 5. Hoods 8, preferably of conical form, are mounted for 50 sliding movement on the top 3 and coöperates with the openings 7. The side walls of the hoods 8 are supplied with openings 9. Delivery members 10, which may be of 55 trough-shape, project toward each other,

from the adjacent sides of the hoods 8, the delivery members being located externally of the hoods.

The numeral 11 marks an arch support secured to the top 3 about midway between the ends thereof. The support 11 is adapted to uphold the upper arm 12 of a U-shaped generator 14, including a lower arm 15 passing through the openings 9 in the hoods 8, the lower arm 15 of the generator being 65 provided with combustion orifices 16 located within the hoods 8. Flame spreaders 17 are supported on the upper arm 12 of the generator 14 and are located above the hoods 8. 70

In practical operation, when the parts 75 are arranged as shown in Fig. 2, the air draws upwardly through the casing 1, through the openings 7 and through the hoods 8. The oil traverses the arm 12 of the generator 14 and enters the arm 15 thereof, the fuel, in the form of a gas, burning at the combustion orifices 16, a mixture of gas and air being produced within the hoods. The structure is adapted to be placed in a cook stove, if desired, and the 80 operation above outlined is common and thoroughly understood in the art.

Let it be supposed that, at the starting of the operation, it is desired to deposit a priming charge on the absorbent material 6 85 in the tray 5, so as to heat up the generator 14 initially. Then, the hoods 8 are slid outwardly, in opposite directions, until the combustion orifices 16 discharge on the delivery members 10, the oil flowing from the 90 delivery members, upon the absorbent material 6, or into the tray 5. In this way, a priming charge may be deposited in the tray, or on the absorbent material, the priming charge being ignited for the purpose of 95 heating up the generator. The hoods 8 then may be slid inwardly, toward each other, into the positions shown in Fig. 2, the hoods abutting against the upstanding ends of the tray 5, and the combustion orifices 16 being 100 disposed within the contour of the hoods 8.

Having thus described the invention, what is claimed is:—

1. In a device of the class described, a 105 casing having a priming tray and provided with an opening; a U-shaped generator supported above the casing and embodying upper and lower arms, the lower arm being supplied with a combustion orifice; a hood coöperating with the opening and having a 110

laterally projecting discharge member, the hood being slidable on the lower arm of the generator, whereby one end of said discharge member may be disposed below the 5 combustion orifice when the other end of said member is disposed above the tray, thereby to deposit a priming charge in the tray.

2. In a device of the class described, a 10 casing; absorbent material on the casing; a U-shaped generator supported above the casing and embodying upper and lower arms, the lower arm being supplied with a combustion orifice; a hood having a laterally projecting discharge member, the casing having an opening coöoperating with the hood, the hood being slidably mounted on the casing, whereby one end of the discharge member may be disposed below the 15 combustion orifice when the other end of said member is disposed above the tray.

20 3. In a device of the class described, a

casing including a top provided with means for receiving a priming charge, the top being provided with an opening; a U-shaped 25 generator supported above the top of the casing and embodying upper and lower arms, the lower arm being supplied with a combustion orifice; a hood coöperating with the opening and having a laterally projecting discharge member; and means for supporting the hood slidably, whereby one end of the discharge member may be disposed below the combustion orifice and the other end of the discharge member disposed above 30 the means for receiving the priming charge.

In testimony that I claim the foregoing as my own, I have hereto affixed my signature in the presence of two witnesses.

CARL E. BROWN.
